FIG. 3

Des. 186,104

PAGE 4

FIG. 4

FIG. 5FIG. 6Fig. 1 is an elevational view of one side of a dental chair showing my new design;

Fig. 2 is an elevational view of the other side;

Fig. 3 is a front elevational view;

Fig. 4 is a rear elevational view;

Fig. 5 is a front elevational view of the underside; and

Fig. 6 is a fragmentary side elevational view thereof.

The dominant features of my design reside in the portions shown by full lines in the drawings.

I claim:

The ornamental design for a dental chair, as shown and described.
